UNITED STATES PATENT OFFICE

114,374

DESIGN FOR A COUNTER SCALE

Sidney R. McKinney, Oklahoma City, Okla.

Application December 23, 1938, Serial No. 73,838

Term of patent 14 years

To all whom it may concern:

Be it known that I, Sidney R. McKinney, a citizen of the United States, residing at Oklahoma City, county of Oklahoma, State of Oklahoma, have invented a new, original, and ornamental Design for a Counter Scale, of which the following is a specification, reference being had to the

accompanying drawing, forming a part thereof.

The figure is a perspective view of a counter scale, showing my new design.

I claim:

The ornamental design for a counter scale, substantially as shown.

SIDNEY R. MCKINNEY.
